SHOE LAST

Wilhelm F. K. Karow, Jackson, Miss.

Application August 5, 1931, Serial No. 555,189

2 Claims. (Cl. 12—133)

This invention relates to shoe lasts and shoe manufacturing.

One object of the invention is to provide a device of this character which is perfectly form fitting to the human foot.

Another object of the invention is to provide a device of this character providing for a shoe sole structure conforming to the exact contour of the sole of the human foot.

10 Another object of my invention is to provide a device of this character adapted to mold a shoe structure which by its natural embodiment is an arch support.

Still another further object of the invention is 15 to provide a device of this character which is a form for a perfect shoe heel structure.

A still further object of my invention is to provide a device of this character adapted to mold a shoe forming a perfect fit to the human foot, and 20 thereby preventing a misfitting of shoes to the foot.

Still other objects of the invention will be disclosed upon reading the specifications in connection with the accompanying drawing.

25 In the drawing. Figure 1 is a side view of the device modeled for the right foot.

Figure 2 is a bottom view thereof.

Figure 3 is a front cross sectional view thereof 30 taken on the line 3—3 in Figure 2.

Figure 4 is a rear view thereof.

Following the drawing, in detail the last 1 is of ordinary structure having a base or sole 2. The last shown is for the right foot, and has the outer 35 contour line of the sole 2 shaped in a straight line 3 from the side of the heel 5 to the point 5a which is at the predetermined position of the little toe of the foot and past the outer terminus of the usual break line, thus following the exact 40 line of the foot to the little toe, the sole 1 then inclines inward to a natural point shown in Figure 2.

The Figure 2 in the drawing shows the inner 45 contour line of the sole 2 of the last 1 extending in a normal manner from the toe in a rearward direction to the point 6a which indicates the inner terminus of the usual break line of a foot and then extending inwardly approximately along said break line for a distance substantially past the median line of said last 1. In the drawing, 50 it will be observed that the width of the sole 2 at its narrowest point 2a is but approximately one third the width of the last 1 and is designed to represent the portion of the shank of a normal foot that ordinarily is in contact with a level

surface when the foot is flat thereon. It is to be understood, of course, that in the adaptation of my invention to an abnormal foot, the width of the sole 2 at 2a may vary somewhat and may be more than one-third and less than one-half the 60 width of the last. From this point 2a the inner contour line extends rearwardly in a gradual outward curve to the inner terminus of the breast line of the last. From the breast line rearwardly to the heel end of the last, the inner contour line is extended in a normal manner. The inner side X of the last 1 is cut away to 4, following the natural contour of the human instep to a junction with the inner edge of the sole of the last.

The last 1 follows rearwardly a practically 70 straight line to either side of the heel at 5 and 6, sloping slightly inwardly and then following a straight line up from 6 to 7, to the top 9 of the last and having a decided curve inwardly at 8 from the side 5 to the top of the last 9, thus following the exact contour of the human heel.

75 It is thus to be seen that the last which I have invented is modeled on the exact contour of the human foot; and, that the sole of a shoe modeled on this last will follow the exact contour of the 80 surface engaging portion of a human foot. It will also be apparent that the portion of the upper of such a shoe which is attached to the inner side of the narrow shank of the sole will snugly embrace the instep and positively support the same, 85 yet allowing freedom of action. It is thus apparent that the use of built in inflexible arch supports, or inflexible arch supports of any kind, is unnecessary in a shoe constructed on my last, 90 as the upper itself provides a flexible support for the arched instep. A shoe constructed on this last also follows the exact contour of the heel of the foot, and acts as a brace in support for the foot within the shoe. Thus, it is apparent that in fitting a shoe built on this last, to the foot, a perfect fit must necessarily be accomplished, otherwise the break line of the shoe will not be correctly placed with respect to the foot and the shoe 95 will not be wearable.

100 It is to be of course understood that while I have shown and described one form of my invention, various alterations and changes may be made in it without departing from the spirit thereof, and that I do not wish to be restricted to the precise structure disclosed but hold myself entitled to make such changes therefrom as fairly fall within the scope of what I claim.

105 What I claim is:
 1. A shoe last having a heel portion forwardly defined by a breast line, a ball portion rearwardly 110

- defined by a usual break line, and an intermediate shank portion, the outer contour line of said heel, shank, and the rear part of said ball portion being in a substantially straight line, and the inner contour line of said shank extending inwardly approximately along said break line for approximately two thirds the width of the last and then being gradually curved outwardly to the breast line.
- 5 10 2. A shoe last having a heel portion forwardly defined by a breast line, a ball portion rearwardly

defined by a usual break line, and an intermediate shank portion, the outer contour line of said heel, shank, and the rear part of said ball portion being in a substantially straight line, and the inner contour line of said shank extending inwardly 80 approximately along said break line for a substantial distance past the median line of the last and then being gradually curved outwardly to the breast line.
